US0D1061964S

(12) **United States Design Patent** (10) **Patent No.:** **US D1,061,964 S**
(45) **Date of Patent:** **** Feb. 11, 2025**

(54) **VEHICLE HEADLIGHT**

(71) Applicant: **Ford Global Technologies, LLC**,
Dearborn, MI (US)

(72) Inventors: **Soohyoung Kim**, Northville, MI (US);
Damon G. Depyster, Plymouth, MI (US); **William Mangan**, Ypsilanti, MI (US)

(73) Assignee: **Ford Global Technologies, LLC**,
Dearborn, MI (US)

(**) Term: **15 Years**

(21) Appl. No.: **29/827,245**

(22) Filed: **Feb. 18, 2022**

(51) LOC (15) Cl. **26-06**

(57) **CLAIM**

The ornamental design for a vehicle headlight as shown and described.

DESCRIPTION

FIG. 1 is a front elevational view of a vehicle headlight showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The broken lines and portions of the vehicle headlight surrounded by broken lines and shown deemphasized form no part of the claimed design.

1 Claim, 7 Drawing Sheets
